UNITED STATES PATENT OFFICE.

LOUIS H. ROSSUCK, OF LINDENHURST, NEW YORK, ASSIGNOR TO ROSSUCK MANUFACTURING COMPANY, OF CHICAGO, ILLINOIS, A CORPORATION OF ILLINOIS.

CLASP.

No. 889,969.

Specification of Letters Patent.

Patented June 9, 1908.

Application filed May 16, 1907. Serial No. 373,942.

To all whom it may concern:

Be it known that I, LOUIS H. ROSSUCK, a citizen of the United States, residing at Lindenhurst, in the county of Suffolk and State 5 of New York, have invented certain new and useful Improvements in Clasps, of which the following is a specification.

My invention relates in general to clasps, and more particularly to fastening devices 10 for detachably uniting parts of garments or separate garments.

The primary object of my invention is to provide a clasp which may be readily secured to a garment and which will be securely held 15 in the desired position without injuring the garment to which it is attached.

A further object of my invention is to provide an improved clasp which will be simple in construction, inexpensive in manufacture 20 and efficient in use.

The embodiment of my invention herein disclosed may be generally described as consisting of a clip comprising two substantially parallel portions united by an integral end 25 portion, an U-shaped spring located within the clip and having a slot adjacent one end surrounding projections extending inwardly from one member of the clip, a lever pivotally mounted within an opening in the 30 opposite member of the clip from that on which the projections are located, a tongue on the lever having a notch adapted to straddle a rib on the adjacent surface of the spring, a hook formed integrally with the 35 clip and having an opening therethrough formed by the metal which is bent to form the outer member of the clip.

My invention will be more fully described hereinafter with reference to the accompanying drawing in which the same is illustrated 40 as embodied in a convenient and practical form, and in which—

Figure 1 is a perspective view; Fig. 2, a side elevational view; Fig. 3, a vertical central sectional view; Fig. 4, a perspective view of the spring and lever detached from the clip; and Fig. 5, a perspective view of the clip, the spring and lever having been disconnected therefrom.

50 The same reference characters are used to designate the same parts in the several figures of the drawing.

Reference characters A' and A² designate the side portions of a clip, while reference 55 character A indicates an integral end por-

tion uniting the side portions of the clip. When the clasp is adapted for use to support underwear, the clip may be conveniently formed integrally with a hook B having a downwardly bent portion b. The outer side 60 portion A' and the end portion A of the clip are formed by cutting the metal of the hook B and bending the same downwardly, as clearly shown in the figures of the drawing.

Located within the clip is an inverted U- 65 shaped spring comprising portions C' and C² adapted to engage the inner surfaces of the portions A' and A² of the clip. The portion C² of the spring is provided with an elongated slot c² adjacent the end thereof which 70 surrounds projections a² extending inwardly from the portion A² of the clip. The outer surface of the portion C' of the spring is provided with a rib c'.

D designates a lever having a tongue D' 75 extending within an opening a' in the portion A' of the clip. The lever is provided with pintles d, d which engage within recesses a formed in the inner surface of the portion A' of the clip. The tongue D' is provided with 80 a notch d' adapted to straddle the rib c' on the spring.

The portion A' of the clip is provided with a notch a³ located adjacent the fulcrum of the lever D and into which the lower edge of the 85 rib c' is adapted to be received when the lever is oscillated upwardly to the position shown in Fig. 1. The opening a' through the portion A' of the clip is notched transversely at its upper end to form a recess within which 90 the end of the lever D is adapted to lie when the lever is moved inwardly to the position shown in Figs. 2 and 3, such transverse enlargement of the opening a' serving to permit the end of the lever to be readily engaged to oscillate the same outwardly.

The manner of using my improved clasp is as follows: The lever D is oscillated outwardly to the position shown in Fig. 1, which permits the spring to expand so that the portions thereof will lie in close contact with the inner surfaces of the adjacent portions of the clip. The clip may then be readily passed around the portion of a garment, or the material, which is to be grasped, after which the 100 lever is oscillated from the position shown in Fig. 1 to that shown in Figs. 2 and 3. This movement of the lever forces the portions C' of the spring inwardly so that the projections c² thereon will be moved into close proximity 105

to the projections a^2 on the member A^2 of the clip. The opposing projections c^3 and a^2 serve to tightly grasp the interposed material. The spring is held in such compressed 5 position by the tongue D' and is prevented from being disconnected from the clip by the groove d' in the tongue straddling the rib c' on the adjacent portion of the spring, and also by the elongated slot c^2 in the other portion 10 of the spring surrounding the projections a^2 on the clip.

When it is desired to disengage the clasp from the garment, the lever D is swung outwardly by exerting pressure on the end of the 15 lever, so that the tongue D' is oscillated to a position within the opening a' in the clip. This movement of the tongue permits the spring to expand and release the garment so that it may be removed from between the 20 projections c^3 on the spring and the projections a^2 on the clip. When the spring is in its expanded condition it is retained within the clip not only by the projections a^2 extending through the slot c^2 , but also by the 25 lower end of the rib c' being received within the notch a^3 in the portion A' of the clip.

When the clasp used is for the purpose of supporting underwear and is embodied in the form shown in the drawing, the hook B is engaged with the top of trousers after the clasp 30 has been secured to the underwear.

While I have shown my improved clasp as adapted for use in supporting underwear, yet it will be readily understood that it is adapted 35 for a variety of uses and may be provided with any suitable attaching device in lieu of the hook B , or, in fact, in some uses of the clasp no attaching device is necessary.

From the foregoing description it will be 40 observed that I have invented an improved clasp for engaging garments, or other ma-

terial, which will securely clamp the engaged portion of the garment without injuring the same, and which may be readily engaged with or disengaged from the garment. 45

Having now fully described my invention, what I claim and desire to secure by Letters Patent, is—

1. In a clasp, the combination with a clip comprising two side portions united by an integral end portion, one of said side portions having an opening therethrough, of a U-shaped spring located within said clip and having a rib formed thereon, an oscillating lever extending through the opening in said clip and having a tongue adapted to engage and compress said spring, said tongue having a notch adapted to straddle said rib and thereby hold said spring within said clip when compressed, said clip having a notch in 60 which said rib is received when the spring is expanded. 55

2. In a clasp, the combination with a clip comprising two side portions united by an integral end portion, one of said side portions having an opening therethrough and the other of said side portions having inwardly projecting points, of a U-shaped spring located within said clip, an oscillating lever extending through an opening in said clip and having a tongue adapted to engage said spring and force the interposed material of a garment against said points, the outer end of said lever being curved to extend around and lie within an opening in the end portion of 70 said clip when said lever is oscillated to grip the interposed material. 75
